(57) **CLAIM**

I claim the ornamental design for double ended socket, as shown and described.

DESCRIPTION

FIG. 1 is a perspective view of a front, top, and left side of the double ended socket;

FIG. 2 is a top plan view of the double ended socket of FIG. 1;

FIG. 3 is a right-side elevational view of the double ended socket of FIG. 1;

FIG. 4 is a left-side elevational view of the double ended socket of FIG. 1;

FIG. 5 is a front elevational view of the double ended socket of FIG. 1;

FIG. 6 is a rear elevational view of the double ended socket of FIG. 1; and,

FIG. 7 is a bottom plan view of the double ended socket of FIG. 1.

The broken line portion of the figure drawings is included to show portions of the article that form(s) no part of the claimed design.
